ARTIFICIAL LEG AND KNEE JOINT
THEREFOR

Joseph A. Mazzola, Endicott, N. Y.

Application July 23, 1947, Serial No. 762,948

6 Claims. (Cl. 3—2)

1

The present invention relates to prosthetic devices and more particularly to an artificial leg construction which, when in actual use, will enable an above-the-knee amputee to accurately reproduce the normal walking gait.

It is among the principal objects of the invention to produce an artificial leg having a novel type of flexible knee joint which is capable of bearing the full weight of the user at any angle of flexure between the axes of the thigh and calf sections of the artificial leg construction.

Another and equally important object of the invention is to provide a leg construction of the nature outlined above which will permit changing of the angle of flexure while the weight of the user is being supported by the knee joint.

A still further object of the invention is to provide an artificial leg having a flexible knee joint which is so constructed as to permit flexing between the thigh and calf sections, in the normal manner of thigh and calf flexure, either in free fashion or under load and throughout the maximum useful angle, yet which at the same time will prevent abnormal reverse flexing and consequent collapse of the joint under the influence of weight applied thereto.

Another object of the invention is to provide an artificial leg construction of the character set forth above and having a foot section provided with a flexible toe extension which, upon flexing due to normal contact with the ground, releases the knee joint for flexing until such time as the foot section has left the ground and the toe extension again becomes normally extended. The toe extension is also operable when the knee joint is partially flexed to release the same for further flexing.

Still another object of the invention is to provide an artificial leg construction having thigh, calf and foot sections, the latter including a toe extension, and in which the thigh and calf sections have interposed therebetween a resilient shock absorbing medium which operates to prevent sudden impact between these two parts when the angle of flexure becomes a straight angle and the two sections move into alignment at the end of each step cycle after the foot section leaves the ground. Similar objects of the invention reside in the provision of a resilient shock absorbing medium between the toe extension and the foot section proper and also between the foot section proper and the calf section to relieve rigidity between these parts when the same are in substantial abutting relationship.

The provision of an artificial leg possessing the 55 depend for their rigidity and their ability to carry

2

features outlined above, one which is relatively simple in its construction; one which is possessed of a minimum number of moving parts and which consequently is unlikely to get out of order; one which is rugged and durable; one in which many of the parts may be constructed of light sheet metal stampings thus eliminating objectionable overall weight; one which may be manufactured at a low cost; one which is attractive in appearance and design; one which is silent in its operation; one which may be worn for long periods of time without discomfort to the user; and one which otherwise is well adapted to perform the services required of it, are further desiderata that have been borne in mind in the development and production of the present invention.

In the accompanying single sheet of drawings:

Fig. 1 is a side elevational view of an artificial leg constructed in accordance with the principles of the present invention. In this view certain parts have been broken away to more clearly reveal the nature of the invention.

Fig. 2 is a sectional view taken substantially along the line 2—2 of Fig. 1.

Fig. 3 is an enlarged view similar to Fig. 2 with certain parts removed for the sake of clarity.

Fig. 4 is a sectional view taken substantially along the line 4—4 of Fig. 3.

Fig. 5 is a sectional view taken substantially along the line 5—5 of Fig. 1; and

Fig. 6 is a diminutive side elevational view, partially schematic in its representation, illustrating certain principles of operation associated with the invention.

In all of the above described views like characters of reference are employed to designate like parts throughout. These views show a right leg assembly.

Referring now to the drawing in detail, the improved artificial leg involves in its general organization a thigh section 10, a calf section 12 and a foot section 14, the latter including a toe section or extension 16 which is hinged as at 18 to the foot section proper. The leg also includes a lever 24 which is hinged as at 26 to the thigh section 10 and which, for convenience of description and claim terminology, may well be termed as the torso or abdominal section inasmuch as this lever is actuated during relative flexing movements between the torso and thigh of the user to accomplish a function that will be made clear presently.

As shown, the thigh and calf sections 10, 12

a load upon the nature of their respective shell like cosmetic exterior portions. These substantially cylindrical hollow shells are patterned after the size and shape of the human limbs and are formed of a sturdy material, such as laminated wood, fiber, plastic or the like, and they may constitute the main support for the various movable or stationary mechanical fittings and accessories associated with the invention.

As shown in Fig. 1, a plate or bracket 20 is riveted as at 22 or is otherwise secured to the outside of the thigh section 10 at the top thereof and projects a slight distance above the upper rim of the section. The previously mentioned lever 24, which for convenience of description of claim terminology may in itself be regarded as the torso section of the artificial leg, is hinged as at 26 to the bracket 20 and has its upper end secured by means of a plate 28 to a pelvic band or strap 30 which is preferably formed of leather and which is padded as at 32 for the comfort of the user. The strap is adapted to be positioned around the abdomen of the user while the thigh or stump from which amputation has been made is adapted to be received in the hollow thigh section 10. The abdomen or torso and thigh have been illustrated in dotted lines at 34 and 36, respectively. The function of the lever 24 will be made clear presently.

The thigh section 10 is in the form of a slightly tapered hollow substantially conic section and the lower end thereof has fitted on the inside a steel or other metal ring-like insert 38 having depending therefrom a pair of ears 40 and 42 which form a part of a special locking hinge construction or knee joint which has been designated in its entirety at 44.

The knee joint 44 also includes a pair of ears 46 and 48 which are formed on a ring-like member or sleeve 50 which surrounds and is secured to the upper end of the calf section 12. A pin or through bolt 52 is supported at its opposite ends centrally in the ears 46 and 48 and extends transversely across the section and passes through the ears 40 and 42. The through bolt is pinned as at 54 against turning movement relative to the ears 46 and 48 and is thus constrained to move bodily with and follow the swinging movements of the calf section 12.

The bolt 52 is formed with a medial threaded section or portion 55 and has threadedly received thereon one abutment element 56 of a clutch-like assembly whose counterpart is in the form of an extension or abutment 58 formed on the collar 42. The element 56 is provided with a pair of teeth 59 thereon and the member 58 is provided with a pair of similar and mating teeth 60. The surfaces of the members 58 and 60 between the extremities of the teeth are inclined as shown at 62 in Fig. 4 and afford mating inclined contact surfaces designed for engagement when the member 56 is turned on the through bolt 52 and wedged against the member 58.

The lever 24 is formed with a rearward extension or arm 66 which is offset to project outside the conical confines of the thigh section 10 and this extension is connected by means of a cable 68 to the element 56 on which it is wound in the manner of a drum winding. A second cable 69 winding on the member 56 is attached to one end of a coil spring 70 and the other end of the spring is attached to an internal lug 72 formed on the inside of the calf section 12. The member 56 is thus biased to turn in a counterclockwise direction as viewed in Fig. 1 for mating engage-

ment of the teeth 59 and 60 and of the inclined surfaces 62.

From the above description it will be seen that the through bolt 52 constitutes a hinge pin or pintle by means of which the thigh and calf sections 10 and 12 are pivotally connected together. The two sections are capable of flexing with respect to each other and, in the erect position of the artificial leg where the two sections are in substantial alignment, reverse or abnormal flexing of the structure is prevented by means of a yieldable pad or bumper 74 which is suitably attached to the calf section and which occupies a position on the forward side of the structure between the upper rim of the calf section and the lower rim of the thigh section. The pad 74 may be formed of any suitable yieldable material such as rubber and it serves to prevent sudden impact between the rim portions of the two sections and consequently to eliminate sudden impact between the two parts and consequent sound and vibration.

The strength of the spring 70 is relatively great and as a consequence the knee joint section or element 56 is biased on the threaded portion 55 of the bolt 52 so as to bear against the section 58 with a fair degree of pressure and to resist any normal camming action that would ordinarily tend to occur if a torque were to be applied to either section tending to cause relative flexing between them. This resistance to such torque is made possible by virtue of the relative small pitch of the threads on the portion 55 of the bolt 52. Thus, when the thigh and calf sections 10 and 12 are in alignment and the weight of the user rests upon the structure any tendency of the sections to flex relative to each other is prevented by the inability of the element 56 to yield or "back up," so to speak, on the threads 55. The structure in this erect position is a rigid one and is not subject to collapse. The spring 70 is provided primarily to return the element 56 to its position of engagement with its counterpart element 58 when the thigh and calf sections are straightened into alignment.

In order to permit knee flexure during the normal walking gait, considering only the arrangement of parts thus far described, flexure of the toe extension 16 due to contact with the ground or other supporting surface will cause clockwise movement of the lever 92 and the consequent application of tension to the cord 94. The element 56 will thus be turned in a clockwise direction as viewed in Fig. 1 and, in so moving, this element will be backed away from its counterpart element 58 on the threads 55. Such motion of the element 56 will also serve to separate the teeth 59 and 60 a predetermined distance, depending upon the extent of relative flexure between the torso and the thigh section 10. Inasmuch as, during this relative movement between the two clutch elements 56 and 58, the inclined surfaces 62 thereof become separated, the calf section 12 will then be free to swing rearwardly relative to the thigh section 10 until such time as the lost motion between the two elements 56 and 58 is taken up on the action of the spring 70 and cord 69 after the foot section has left the ground or supporting surface.

Loosening of the knee clutch or joint 44 to permit knee flexing may also be caused by the simple expedient of swinging the thigh or stump 36 forwardly and this motion will have the same effect as bending the body or torso forwardly. Either of these motions will apply a tension to the

cord 68 to unwind the latter from the rotatable clutch element 56 and separate the clutch teeth 59, 60 to permit free flexing of the knee joint. Such anatomical movements on the part of the amputee will be resorted to when mounting a flight of steps or an incline.

When proceeding up a steep incline or mounting a staircase, the extent of forward inclination of the body and of forward swinging elevation of the thigh will be quite marked. The amount of elevation which it is desired to attain at each step will be governed by the relative amount of flexing between the body and thigh performed by the user of the artificial leg and thus with a little experience various grades of elevation may successfully be encountered.

The foot section proper 14 may be in the form of a substantially solid block-like structure constructed of wood, plastic material, light metal or other suitable material. As shown in Fig. 1, an insert or block 80 is embedded in the foot section and is provided with an upwardly extending ear 82 substantially centrally of the section. A bolt or pintle pin 84 is secured in the ear 82 and serves to support thereon a pair of relatively heavy metal straps 86 which are bolted or otherwise secured as at 88 to the opposite sides of the calf section 12. The calf section is thus hingedly supported from and connected to the foot section 14. A rubber shock absorbing medium 89 is inserted in a recess formed in the block 80 and bears against the underneath edges of the two strap members 86.

A rock shaft 90 extends across the calf section 12 and is supported at its ends in the two straps 86 adjacent the top thereon while a bell crank lever 92 is pivoted medially on the shaft 90. One arm of the lever 92 projects forwardly and has secured thereto the lower end of a cord 94. The cord 94 extends upwardly and is wound around and secured to the clutch element 56 as shown in Fig. 2. The direction of winding of the cord 94 on the clutch element 56 is such that clockwise turning movement of the lever 92 will apply tension to the cord 94 to rotate the element 56 in a clockwise direction as shown in Fig. 1 to thus cause this element to move away from its counterpart element 58 and disengage the clutch teeth 59, 60.

The lever 92 is provided with a downwardly extending arm, the lower end of which is pivotally connected to a thrust rod 98 which is inclined forwardly and downwardly and the forward end of which loosely rests upon a rubber insert 100 which is interposed between the toe extension 16 and the foot section proper 14 with its extreme outer end occupying a position slightly rearwardly of the toe extension 16 and normally out of contact therewith.

It will be seen from the above description of parts that during the normal walking gait, when the calf section 12 assumes a forwardly inclined position with the toe extension 16 resting squarely upon the ground and with the heel portion 102 of the foot section proper 14 elevated, the rubber insert 100 will become compressed while, at the same time, one surface of the toe extension 16 will engage the forward end of the thrust lever 92 and apply a torque to the bell crank lever 92, tending to rock this lever in a clockwise direction. Such movement of the lever 92 will apply a tension to the cord 94, thus unwinding the same from the element 56 and turning the latter so as to disengage the clutch teeth 59 and 60 to provide a lost motion between the two parts 56 and 58.

which may be taken up by further flexing of the knee joint.

A yieldable insert 106 is disposed between the lower rim of the calf section 12 and the heel portion 102 of the foot section proper 14 to prevent looseness of the latter section on the calf section and to take up any shocks that might exist and to eliminate any sudden impact and consequent shock that might exist during normal relative movements between these two parts. A cord 108 has its ends attached in any suitable manner to the foot and calf sections and thus serves to apply a plantar or forward tilting movement to the foot section 14 during walking to elevate the heel portion 102 from the ground and permit flexing of the toe section 16.

From the above description it will be seen that there has been provided a prosthetic device in the form of an artificial leg having a novel type of locking knee action which will support the entire weight of the body at any angle of flexure between the thigh and calf sections of the structure, yet which, at the same time, will permit ready release of the locking action when the structure is relieved of its supporting weight. The degree of knee flexure is adapted to be controlled at the will of the user, either by wilful forward inclination of the torso by application of pressure to the supporting surface or ground by the flexible toe extension which forms a part of the foot section, or by any such combination of these two factors as is found to be a part of the normal gait of the user.

It will be appreciated that the present prosthetic device is, for reasons previously outlined, adapted for use in the normal manner of locomotion for walking operations, both on level and inclined surfaces as well as for mounting stepped surfaces, such as a flight of stairs. The artificial leg is also adapted to accommodate itself for sitting positions wherein the thigh section thereof remains substantially horizontal while the calf section assumes a substantially vertical position. This latter feature is made possible by virtue of the fact that in a normal sitting position the axis of the abdominal or pelvic regions assumes approximately a ninety degree angle with the axis of the thigh section. In the artificial leg structure described above, this results in a wide swinging movement of the lever 24 and a consequent large displacement of the rotatable portion or section 56 of the locking knee joint. Such a displacement releases the calf section for swinging movement throughout an angle of at least ninety degrees which is sufficient to permit the calf section to assume a vertical position with the foot section 14 resting on the floor.

When in a sitting position the amputee may even exceed a ninety-degree flexure between the thigh and calf section and assume a position with the calf section inclined rearwardly and with the foot section 14 beneath the chair or other support and directly beneath the vertical axis of the torso. In other words, the seated amputee may even draw his foot in beneath the chair upon which he is seated. Such a position is often normally assumed and in the artificial leg structure this is made possible by flexure of the toe extension 16 and raising of the heel portion 102 from the floor. Such a condition further releases the knee clutch 44 through the action of the cable 94 as previously explained.

While there have been shown and described and pointed out the fundamental novel features of the invention, as applied to a preferred em-

bodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In an artificial leg construction, a thigh section and a calf section, a pintle element secured to one of said sections and pivotally connecting the two sections together with relative flexing movement from a position of substantial alignment to a position of acute angle flexure, an abutment or clutch element mounted on the other section, a second abutment or clutch element, said pintle element being formed with threads thereon upon which said second abutment element is threadedly received, yieldable means normally applying a torque to said second abutment element in a direction to urge the same into engagement with said first abutment element to prevent initial flexing between the sections when they are in substantial alignment, and means operable by independent movement of an anatomical portion of the body of the user for applying a predetermined amount of reverse or counter torque to said second abutment element to remove the latter from said engagement with said other abutment and permit a commensurate amount of relative flexing between said sections.

2. In an artificial leg construction, a thigh section and a calf section, a pintle element secured to one of said sections and pivotally connecting the two sections together for relative flexing movement from a position of substantial alignment to a position of acute angle flexure, an abutment or clutch element mounted on the other section, a second abutment or clutch element, said pintle element being formed with threads thereon upon which said second abutment element is threadedly received, yieldable means normally applying a torque to said second abutment element in a direction to urge the same on said threads into engagement with said first abutment element to prevent initial flexing between the sections when they are in substantial alignment, and means operable upon relative flexing movement between the torsal axis of the user and the axis of said thigh section for applying reverse or counter torque to said second abutment element to remove the latter from engagement with said other abutment element and permit a degree of relative flexing between said sections which is proportionate to the degree of relative flexing movement between said torsal axis and the axis of said thigh section.

3. In an artificial leg construction, a thigh section and a calf section, a pintle element secured to one of said sections and pivotally connecting the two sections together for relative flexing movement from a position of substantial alignment to a position of acute angle flexure, an abutment or clutch element mounted on the other section, a second abutment or clutch element, said pintle element being formed with threads thereon upon which said second abutment element is threadedly received, yieldable means normally applying a torque to said second abutment element in a direction to urge the same along said threads into engagement with said first abutment element to prevent initial flexing between the sections when they are in substantial alignment, a cord secured to said second

abutment element and operable upon the application of tension thereto to apply a reverse or counter torque to the latter to remove the same from engagement with said other abutment element and permit a predetermined amount of relative flexing between said sections and means for attaching said cord to an anatomical portion of the body of the user whereby movement of said anatomical portion in one direction relative to said thigh section will apply tension to said cord.

4. In an artificial leg construction, a thigh section and a calf section, a pintle element secured to one of said sections and pivotally connecting the two sections together for relative flexing movement from a position of substantial alignment to a position of acute angle flexure, an abutment or clutch element mounted on the other section, a second abutment or clutch element, said pintle element being formed with threads thereon upon which said second abutment element is threadedly received, yieldable means normally applying a torque to said second abutment element in a direction to urge the same into engagement with said first abutment element to prevent initial flexing between the sections when they are in substantial alignment, a bell crank lever pivoted to said thigh section, means operatively connecting an arm of said lever to the pelvic region of the user whereby forward inclination of the torso will cause inclination of said lever, a cord connected to another arm of said lever and to said second abutment member whereby movement of said lever to its inclined position will apply reverse or counter torque to said latter element to remove the same from engagement with said other abutment element and permit a predetermined amount of relative flexing between said sections.

5. In an artificial leg construction, a thigh section and a calf section, a pintle element secured to one of said sections and pivotally connecting the two sections together for relative flexing movement from a position of substantial alignment to a position of acute angle flexure, an abutment or clutch element mounted on the other section, a second abutment or clutch element, said pintle element being formed with threads thereon upon which said second abutment element is threadedly received, yieldable means normally applying a torque to said second abutment element in a direction to urge the same into engagement with said first abutment element to prevent initial flexing between the sections when they are in substantial alignment, a foot section mounted on the lower extremity of said calf section and having a toe extension capable of flexing movements relative thereto upon contact with and pressure of the latter on the ground and means operable upon relative flexing between said toe extension and foot section for applying reverse or counter torque to said second abutment element to remove the latter from engagement with said other abutment and permit a predetermined amount of relative flexing between said sections.

6. In an artificial leg construction, a thigh section and a calf section, a pintle element secured to one of said sections and pivotally connecting the two sections together for relative flexing movement from a position of substantial alignment to a position of acute angle flexure, an abutment or clutch element mounted on the other section, a second abutment or clutch element, said pintle element being formed with threads thereon upon which said second abut-

ment element is threadedly received, yieldable means normally applying a torque to said second abutment element in a direction to urge the same into engagement with said first abutment element to prevent initial flexing between the sections when they are in substantial alignment, a foot section secured to the lower extremity of said calf section and having a toe extension capable of flexing movement relative to the foot section, a bell crank lever pivoted to said calf section, means operatively connecting said toe extension and bell crank lever whereby flexing of the former will cause rocking movement of the latter, and means operatively connecting said bell crank lever and second abutment element whereby rocking of the lever will apply reverse or counter torque to said second abutment element to remove the latter from engagement with said other element

and permit a predetermined flexing between the thigh and calf sections.
